BURT LINCOLN WORTHEN, OF TUCSON, ARIZONA TERRITORY.

CIRCULATORY SYSTEM FOR FURNACES

No. 894,869.

Specification of Letters Patent.

Patented Aug. 4, 1908.

Application filed January 3, 1906. Serial No. 294,344.

To all whom it may concern:

Be it known that I, BURT LINCOLN WORTHEN, a citizen of the United States, and a resident of Tucson, in the county of Pima and Territory of Arizona, have invented a new and Improved Circulatory System for Furnaces, of which the following is a full, clear, and exact description.

My invention relates to furnaces, and 10 more especially to furnaces of the various types used for metallurgical processes, such as reduction of ores.

The more particular object of my invention is to utilize the waste heat of the water 15 contained within the water jacket so as to improve the general efficiency of the furnace, and also to prevent the otherwise objectionable effects of the heat. To this end I provide a circulatory system for the water used 20 in the water jacket, the system being so arranged that excessive heat of the furnace is taken up by the water jacket and in turn transferred to the air or analogous aeriform bodies used for supplying the oxygen and the 25 like to the furnace.

Reference is to be had to the accompanying drawings which illustrate as an example the preferred embodiment of my invention, in which drawings like characters of reference 30 indicate like parts throughout the views, and in which

Figure 1 is a side elevation of a furnace equipped with my invention, and showing most of the pipes used in my circulatory system; and Fig. 2 is a vertical cross section through the furnace upon the line 2--2 of Fig. 1 looking in the direction of the arrow, and showing the various connections between the different parts of the water jacket, 40 and also the hydraulic connections relating to the auxiliary drums, the bustle and various other parts.

The supporting posts are shown at 3, the top frame at 4, and the I-beams resting upon 45 the supporting posts and sustaining the weight of the top frame are shown at 5. The upper water jacket is shown at 6 and is surmounted by a water collar 6^a which virtually constitutes a continuation of the jacket 6, 50 and which is provided with inlet pipes 6^b and outlet pipes 6^c. This water collar protects the extreme upper parts of the furnace from excessive heat. The outer wall of the water jacket 6 is shown at 7, and the water contained within the water jacket at 8. 7^a are supporting ribs for bracing the outer wall of

the water jacket. The auxiliary drums are shown at 9, and in communication therewith are tubes 10 (the upper one being removed, see Fig. 2) leading to a gage 11. 60 Each auxiliary drum contains a sinuous pipe 12 located within its upper portion. The upper level of the water contained in the water jacket 6 is kept as nearly as possible constant, and may approximate the center 65 of the auxiliary drums 9 as indicated in Fig. 2. The auxiliary drums 9 are mounted upon necks 13, whereby hydraulic communication is established between the auxiliary drums and the water jacket 6. The bustle is shown 70 at 14 and the bustle pipe at 15. Disposed within the bustle 14 are coils of pipe 16 disposed sinuously as indicated. Supply pipes 17, 18 and 19 lead downwardly from the bustle to the various twyers 20, 21 and 22 for 75 the purpose of supplying air to the same, and at the outer ends of the twyers are caps 20^a, 21^a and 22^a. The lower water jacket is shown at 23, the water contained therein at 24 and the idle air vents at 25, the latter being provided with caps 25^a. Ribs 7^b are provided for supporting the outer wall of the water jacket 23. The metal well is shown at 26, and is formed of clay or other refractory material. This metal well and the lower 80 water jacket 23 are supported upon jacks 27, whereby they may be leveled, and encircling these jacks is a wall 28 of masonry. A water pipe 29, see Fig. 1, for supplying the water is used in my circulatory system. The auxiliary drums 9 are tapped at the bottom by tubes 30 and are thus connected serially together. The coils 12 in the auxiliary drums 9 have no communication with the interior of the drum. The several coils 12 are 85 connected serially by pipes 32, and are arranged so as to occupy the so-called steam spaces or upper portions of the respective auxiliary drums 9. The arrangement is such that a flowing medium may pass successively through these several coils 12 and the pipes 32, without commingling with any water or steam which may wholly or partly fill the auxiliary drums 9. Connected with one of the drums 9 (preferably the last of the 90 series) is a pipe 33, which leads downwardly and is connected to several comparatively short pipes 34, each provided with a hand valve and tapping into the lower water jacket 23 at 36. Upon each side of the furnace a pipe 37 taps into the steam space of an auxiliary drum 9, and leads downwardly to

the bustle 14 upon that side, as indicated in Fig. 1; as the two sides of the furnace are duplicates of each other only one is shown. The coil 16 which constitutes a continuation 5 of the pipe 37, and is inclosed within the bustle 14, has a pipe 39, which is a continuation of the coil 16 and leads to the source of supply for the water; any number of such pipes may be connected together if desired. 10 The upper water jacket is connected with the lower water jacket by U-tubes 41, and these U-tubes are connected with twyer plates 42, so that when the latter are in position, communication is established between the upper 15 and lower water jackets. Valve handles 43, 44, see Fig. 2, are used for controlling the pipes 19 and 20, so as to regulate the supply of air passing therethrough. A tap hole is shown at 45 and a tap spout at 46.

20 In using my invention, water is pumped through the pipe 29 into the coils 12 which, as above described, are inclosed within the respective auxiliary drums 9 and are connected serially together. The water in these 25 auxiliary drums 9 being in open communication with the water 8 in the upper water jacket, tends to assume the same temperature as the water 8. The coils 12, therefore, tend to condense a portion of the steam 30 formed within the auxiliary drums 9. In doing this the coils become heated and transfer their heat to the medium flowing through them, to wit, the water being pumped upward through the water pipe 29. This water, 35 after passing through the various coils 12, descends through the pipe 33, and thus passes into the water jackets 23 and 6, and since these water jackets are in communication on each side by means of the U-tubes 41, 40 it follows that the water passing upwardly through the pipe 29 must ultimately reach the upper water jacket 6 and the auxiliary drums 9. Upon entering the lower water jacket 23 from the pipes 33 and 34, however, 45 the water, being inclosed, becomes warm, and therefore its introduction into the jacket does not produce any chilling effect thereupon.

From all the drums 9 (see the upper left-hand portion of Fig. 1) steam passes downwardly through the pipe 37 into the coil 16, which is inclosed within the bustle 14. The heat radiated from the coil 16 raises the temperature of the medium within the bustle 14, 55 this medium being air. The net result is that the air is heated, whereas the steam is cooled to such a degree that condensation ensues. The water of condensation thereupon passes through the pipe 39 to the source of supply, 60 whence it is again pumped up through the pipe 29 and may be continuously re-used.

As the water evaporating within the system above described does not pass off as steam, but is condensed and used over again, 65 the waste of water is so slight as to become

negligible. This effect may be of great importance in sections where the natural scarcity of water is frequently an impediment to the commercial success of operating furnaces. By the use of my circulatory system a complete cycle of operations is perfected. The 70 destructive heat of the furnace is taken up by water, and this excessive heat thus taken up is utilized for the purpose of raising the temperature of the air or other aeriform body supplied to the furnace, the steam being condensed and returned in the shape of water to the source of supply. Except for the cold water passing through the coils 12, the auxiliary drums 9 would be subjected to continuously increasing steam pressure. If this 75 pressure be relieved by means of a valve, not only is there a waste of energy in the shape of heat units, but there is also a waste of water in the shape of steam passing off. This 80 is prevented by my system, and the water, before it reaches the lower jacket of the furnace, is rendered tolerably warm, as above described.

Having thus described the preferred form 90 of my invention, what I claim as new and desire to secure by Letters Patent is:

1. In a circulatory system for furnaces, the combination of water jackets for taking up excessive heat, a plurality of drums communicating with said water jacket, a plurality of coils connected serially together, and mounted within said drums so as to be heated by steam therein, means for supplying

water to said coils, another water jacket, a 95 connection from one of said coils to said water jacket last mentioned, and means for establishing communication between said water jackets.

2. In a circulatory system for furnaces, the combination of a plurality of water jackets, hydraulic connections intermediate hereof for establishing communication between same, a drum communicating with one of said water jackets, a coiled pipe mounted 100 within said drum and heated by steam therein, and hydraulic connections from said coiled pipe to one of said water jackets.

3. In a circulatory system for furnaces, the combination of an upper water jacket, 115 means for supporting the same, a lower water jacket, means whereby said lower water jacket is supported, a plate provided with twyers and detachably engaging between said upper water jacket and said lower water 120 jacket, and a U-tube mounted upon said plate and adapted when said plate is in position to connect together said upper water jacket and said lower water jacket.

4. In a circulatory system for furnaces, 125 the combination of water jackets for taking up excessive heat, drums communicating with said water jackets to allow for evaporation of water therein, said drums being provided with steam spaces, coils mounted within said

steam spaces of said drums, and connections from said coils to said water jackets for supplying the latter with water.

5. In a circulatory system for furnaces, the combination of an upper water jacket, a lower water jacket, means for establishing hydraulic communication between said upper and lower water jackets, means for supplying hot water to said lower water jacket, 10 and cooling mechanism connected with said upper jacket for condensing steam therefrom.

6. In a circulatory system for furnaces, the combination of a plurality of water jackets, means for establishing communication therebetween, a bustle, a coiled pipe mounted within said bustle, a drum connected with said coiled pipe, and connections from one of said water jackets to said drum.

20 7. In a circulatory system for furnaces, the combination of a water jacket adapted to be heated by waste heat from the furnace, a drum connected with said water jacket, a coil mounted within said drum and adapted 25 to be heated thereby thus partially condensing steam within said drum, a bustle, air pipes connected therewith for supplying air to the furnace, a coiled pipe mounted within said bustle, and hydraulic connections from 30 said bustle to said coil within the same.

8. In a circulatory system for furnaces,

the combination of water jackets in communication with each other, a pipe connected with one of said water jackets, a drum connected with another of said water jackets, 35 said pipe being provided with a portion extending into said drum, thus enabling said portion to partially cool said drum, and means for supplying water into said portion of said pipe.

40 9. In a circulatory system for furnaces, the combination of water jackets for taking up excessive heat, drums in communication with said water jackets and provided with steam spaces, and mechanism mounted with 45 in said steam spaces for condensing the steam formed therein.

10. In a circulatory system for furnaces, the combination of an ore chamber, a water jacket encircling said ore chamber and 50 adapted to take up heat, mechanism provided with steam spaces and connected with said water jacket, and coils mounted within said steam spaces, for condensing steam therein.

55 In testimony whereof I have signed my name to this specification in the presence of two subscribing witnesses.
